UNITED STATES PATENT OFFICE

JAMES W. JOHNSTON, OF MANCHESTER, NEW HAMPSHIRE, ASSIGNOR TO LACENE MANUFACTURING COMPANY, OF MANCHESTER, NEW HAMPSHIRE, A CORPORATION OF MAINE

GRADING MACHINE

Application filed December 16, 1929. Serial No. 414,299.

This invention relates to grading machines for shoe soles, heel lifts, counters, taps and other blanks of stock and particularly to the well-known Nichols type of grading machines shown in a series of Nichols patents of which the Nichols Patent No. 1,130,321 dated March 2, 1915, may be referred to as a characteristic example. Although of more general application the invention will be herein illustrated as applied to the Nichols type of grading machine specifically described in the Cogswell Patent No. 1,726,610 dated September 3, 1929. So much of that machine is herein shown as is necessary to an understanding of the present invention and reference is made to said Cogswell patent for a more complete description of the machine as a whole. For convenience and clarity the same reference numerals, so far as they are applicable, will be used herein as in said Cogswell patent.

A principal object of the invention is to increase the output of the machine without increasing its running speed. This is accomplished by mechanism which makes it possible to feed the blanks through the machine with greater frequency than heretofore, that is, to pass the successive blanks through the machine closer together thereby increasing the number of blanks that the machine will handle in a given length of time. In the Nichols machines of the kind exemplified by the Nichols Patent 1,130,321 it was necessary for the graded blank to pass completely out of the grading mechanism before another blank could be fed into the machine. It was the exit of a blank from the machine which effected the opening of the gate that controlled the feeding-in of another blank to the machine. In later developments as shown, for example, in said Cogswell Patent 1,726,610 the speed of production of the machine was increased by means of a trip member located just in advance of the grading mechanism and actuated by the advance or leading end of the blank just before it entered the grading mechanism to open the gate at the entrance end of the machine and permit the feeding-in of a succeeding blank before the preceding blank

had left the grading mechanism. The same trip also operated the stamping mechanism and the feeding mechanism. While this increased the number of blanks which could be passed through the machine in a given time, there still remained considerable space between successive blanks, and as the trip which controlled the admission of another blank to the machine was actuated by the advance end of the blank in the machine, there was necessarily a greater distance between successive short blanks than between long blanks.

With the present invention the trip for controlling the admission of a succeeding blank and for feeding the latter into the machine is close to the detecting rolls and is operated to permit the succeeding blank to be fed in by the rear or following end of the blank already in the machine almost immediately after the latter blank leaves the detecting rolls. By this device not only does each succeeding blank follow the next preceding blank through the machine at a shorter interval of time and in closer spacing than has heretofore been possible, but the same distance or spacing will be preserved between blanks of all sizes since the admission of a succeeding blank is governed by the following or trailing end of the preceding blank rather than by its leading or advance end, and therefore the spacing between successive blanks is maintained uniform irrespective of their length. Thus with the present invention a new blank is fed into the machine almost immediately after the preceding blank has left the detecting rolls without waiting for the preceding blank, or its advance end at least, to pass the length of the machine before actuating a trip which admits a succeeding blank.

A further feature of the invention is a lock for the grading mechanisms which is controlled by the same trip which controls the admission of the succeeding blank and is held inoperative while a blank is passing through the detecting rolls but is locked immediately after the blank leaves the detecting rolls and remains locked until it is unlocked by the next

succeeding blank immediately after entering the detecting rolls.

A further feature of the invention is a novel mechanism for actuating the stamping or marking device controlled by the skiving or feeding rolls at the outgoing end of the machine.

In the accompanying drawings, which illustrate a preferred embodiment of the invention;

Fig. 1 is a plan view of the machine;

Fig. 2 is a side elevation of the machine;

Fig. 3 is a vertical section on line 3—3 of Fig. 1;

Fig. 4 is a detail of the trip hereinafter described;

Fig. 5 is a vertical section on line 5—5 of Fig. 1;

Fig. 6 is a detail in front elevation and on an enlarged scale of a pair of the wedge blocks hereinafter referred to; and

Fig. 7 is a detail in front elevation and on an enlarged scale of part of the new locking mechanism.

As already stated the grading machine selected for illustrating the present invention is the same in its general construction as that shown in the Cogswell Patent No. 1,726,610, and said patent is incorporated herein by reference for a fuller description of certain details which need not be here repeated in order to understand the present invention.

Referring to the drawings, 1 represents the main shaft carrying at one end a pulley 3 by which the shaft may be continuously driven in the direction of the arrow (Fig. 2). Shaft 1 extends across to the opposite side of the machine where it has fixed on it a pinion 4 meshing with an intermediate gear 5 to drive two gears 6 and 7 (Figs. 1, 2 and 3). The gear 6 is fast on one end of a shaft 8 which extends across the machine and has loosely and slidably mounted upon its opposite end a clutch pinion 9 (Figs. 1 and 3) provided on its outer face with teeth 10 constituting one member of a clutch, whose other member 11 is fixed to and rotates continuously with the shaft 8 and is provided with teeth 12 to co-operate with the teeth of the pinion clutch member 9. The pinion clutch member 9 is yieldingly urged by a spring, not shown, toward the rotating member 11. The inner end of the pinion clutch member 9 is provided with a stud or pin 14 (Figs. 1, 2 and 3) which cooperates with a shipper in the form of a cam arm 15 pivotally mounted at 16 on the frame of the machine. With the parts in the position shown the shipper 15 through its engagement with pin 14 is holding the pinion clutch member 9 out of engagement with the clutch member 11, in which condition the shaft 8 will rotate idly and no stock will be fed into the machine by the feeding mechanism which is actuated through the clutch as presently will be described. If, however, the

shipper 15 is raised against the tension of spring 24 (Fig. 2) until it clears stud 14, the spring pressed clutch pinion 9 will be let into engagement with the clutch member 11.

When the clutch member 9 is in engagement with the constantly rotating clutch member 11 it acts through an intermediate pinion 25 (Fig. 2) to drive a pinion 26 which is fast on shaft 27 journalled on the frame of the machine. Fixed to the inner end of shaft 27 is a crank arm 28 (Fig. 3) connected by a link 29 with a feed slide (not shown) which is reciprocated by the rotation of the crank arm 28 to feed the soles or blanks one by one from the bottom of a stack of blanks S held within the magazine H, as more fully described in said Cogswell Patent No. 1,726,610.

The detecting or measuring mechanism at the ingoing end of the machine consists, as usual, of the upper detecting roll 32 and the lower detecting roll 33, the latter preferably divided into two sections secured to shaft 35. The shaft 35 is journalled in boxes 36 slidably mounted in vertical ways on the frame of the machine and the two boxes are rigidly connected by a crossbar or yoke 37 fastened to their under sides. A pair of bell-crank levers 45 engaging the under side of yoke 37, fulcrumed on the frame of the machine and having their depending arms connected by a spring 47, yieldingly support the lower detecting roll 33 and tend to press the same upward.

The upper detecting roll 32 is mounted on shaft 48 to one end of which is fixed the continuously rotating gear 7. The two shafts 48 and 35 of the detecting rolls are connected by gears 49 and are thereby rotated together.

The continuously driven main shaft 1 also carries a sprocket wheel which is connected by a chain 60 with a sprocket wheel 61 fast on a stud shaft projecting from the frame of the machine. A pinion on sprocket 61 drives a gear 63 fast on shaft 64 extending across the machine. Near the middle of the shaft 64 is a sprocket for driving the usual feed chain indicated in broken lines at 50 (Fig. 2). Thus the feed chain 50 is continuously driven and carries blanks from the feeding and detecting rolls 32, 33, to the skiving and feeding rolls 67 and 68. The skiving rolls 67 and 68 carry the blanks past a stationary knife blade 71. The lower skiving roll 68 is continuously driven from main shaft 1 through pinion 72 fast on the main shaft and gear 73 fast on shaft 74 of the lower skiving roll (Fig. 1). The shaft 75 of the upper skiving roll 67 is also continuously driven from the main shaft 1 by gearing 76, 77, 78.

Both rolls 67 and 68 are journalled in journal boxes which are mounted to slide in vertical ways in the frame of the machine. The lower roll 68 is supported by heavy springs 176; and the journal boxes 158 of the upper

roll 67 are provided with the usual abutments 157 in the form of stepped wedges which cooperate with stepped abutment wedges 156 on the under side of a slide bar 155 mounted to move crosswise of the frame of the machine.

The slide bar 155 is automatically adjusted as usual in response to the measurements of the blanks as determined by the detecting roll 33, to vary the extent of possible upward movement of the upper skiving roll 67 when a blank passes between rolls 67 and 68. A blank passing between rolls 67 and 68 will first lift the upper roll 67 until its abutment wedges 157 seat against the abutment wedges 156 of the slide bar 155, after which the lower roll 68 will yield downwardly against the pressure of its springs 176 more or less according to the amount of stock that is to be cut off from the under side of the blank by the knife 71.

The adjustment of the slide bar 155 not only determines the adjustment of the skiving devices, but also of the marking or stamping wheel 175 through a link 188 connected at one end to the slide bar and at the other end to a gear segment 186 which meshes with a pinion fast on the shaft of the marking wheel 175. The marking wheel 175 and gear segment 186 are mounted on a vertically movable slide 185 which is thrust downwardly to perform the stamping operation by an arm 189 (Figs. 1 and 5) actuated by spring 191.

The setting or transmitting mechanism by which the measurements or thickness detections as determined by the detecting roll 33 are transmitted to the slide bar 155, and so to the grading devices (that is, the skiving or evening device and the marking wheel), is the same as in said Cogswell Patent No. 1,726,610.

The passage of a blank between the detecting rolls 32 and 33 causes the lower roll 33 to move up and down, the thicker parts of the blank depressing the roll 33 and the thinner parts permitting it to rise under the influence of spring 47 (Fig. 3). This detecting or measuring movement is transmitted through the usual lever 133 to the rock shaft 139 and thence to the slide bar 155 by mechanism fully described in said Cogswell Patent No. 1,726,610. It will be understood that grading machines of this kind grade stock in accordance with the thinnest spot in the blank as determined by the detecting rolls and that the thinness measurements are not preserved until the forward end of the blank reaches and lifts trip 174, which is adjustably mounted on rod 173. The lifting of trip 174 lifts rod 169, which depends from arm 170 fixed to the same rock shaft which carries rod 173, thereby letting pawl 166 into ratchet 164 fast on rock shaft 139. This locks the rock shaft 139 against movement in a direction to respond to thicker areas in

the blank being measured by the detecting rolls but permits the rock shaft to turn in a counterclockwise direction in response to successively thinner spots encountered in the blank.

In front of the detecting rolls 32 and 33 there is the usual gate 51 for governing the admission of blanks to the detecting rolls, pivoted at 52 on the frame of the machine and connected by a link 53 with an arm 54 fulcrumed on a stud 55 and carrying at its opposite end a pawl 165. When the rear or trailing end of a blank passes out from under gate 51, the gate drops to the table and acts through link 53 and arm 54 to set pawl 165 into ratchet 163, thus acting in conjunction with pawl 166 to lock the rock shaft 139 against movement in either direction.

The parts thus far described and their operation are substantially the same as more fully shown and described in said Cogswell Patent No. 1,726,610, to which reference is hereby made for further details and a fuller explanation. As these parts do not of themselves constitute the present invention but already exist in the prior art, it is not necessary to describe them more fully herein, the general construction of the machine having been sufficiently indicated to make clear the application thereto of the novel features of the present invention.

In the machine of said Cogswell Patent No. 1,726,610 the reciprocating feeding slide for feeding blanks from the hopper H into the machine, actuated by the link 29, was controlled by a trip (89 in said patent) in the path of the blanks at the rear of the machine near the grading mechanisms (skiving devices and stamping wheel). When this trip was depressed by the forward or leading end of a blank passing through the machine, it caused the clutch members 9 and 11 to engage and actuated mechanism to open gate 51 and feed another blank into the machine. The same trip also caused the stamping wheel to make its stroke and stamp the appropriate grade mark on the blank which actuated the trip. With this construction, as the feeding in of a succeeding blank is controlled and timed by the leading end of the preceding blank when it approaches the rear end of the machine, there was a substantial loss of time between the start of successive blanks; and said loss was greater between short blanks than long blanks since successive blanks were fed in at uniform intervals of time determined by the passage of the leading ends of the blanks and consequently the distance between the following or trailing end of each blank and the leading end of the succeeding blank was greater with short blanks than with long blanks.

In order to increase the output of the machine, that is, the number of blanks passed

through the machine in a given period of time, without increasing the running speed of the machine, and to preserve the same distance or spacing between blanks of all sizes, I have invented a novel tripping mechanism which controls the feeding in of each succeeding blank from the trailing or following end of the preceding blank immediately after leaving the detecting rolls, thus not only causing each succeeding blank to be fed into the detecting rolls at a shorter interval of time after completion of the measurement of the preceding blank, thereby increasing the rate of production of the machine, but also insuring a uniform spacing between the following end of a preceding blank and the leading end of the next succeeding blank irrespective of the size of the blanks.

This tripping mechanism includes a trip member a (best shown in side elevation in Fig. 4) carried by an arm a' , pivoted at a^2 to the usual hold-down shoe 92 which presses the blanks against the feed chain 50. The trip a is adjustable on the arm a' by means of the slot and bolt connection a^4 , a^5 . It is preferably close to the detecting rolls 32, 33 and is on the delivery side thereof and in the path of the blanks, and the front edge of trip a is beveled or inclined at a^8 to cause it to ride up on the advance end of each blank emerging from between rolls 32, 33. The trip a normally rests by gravity on the bed plate 91 of the machine. Extending crosswise of the machine and resting on top of lever a' is a lever b , pivoted to the machine frame at b' . The free end of lever b is curved or bent downwardly and connected to the frame by a tension spring b^2 which normally urges the lever downwardly. A notch or shoulder b^3 on the end of lever b engages the top of one arm of lever c , pivoted to the side of the machine frame at c' . A latch arm d is pivoted to the other arm of lever c . Near its lower end the latch arm d is provided with a tooth d' which normally rests against a stud d^2 on the shipper arm 15 but is adapted under the influence of spring d^3 to engage underneath the stud d^2 when the latch arm d is lowered. The tooth d' is disengaged from underneath the stud d^2 at the proper time by the pin 14 on the clutch pinion 9.

In order to start the machine manually when there is no blank in it to effect the feeding automatically, a hand lever e (Figs. 1 and 3) is provided, fixed to rock shaft f , journaled in a bracket f' fastened to the machine frame. Lever e is connected by a link g to lever b . When the free end of lever e is depressed by hand, lever b is raised, thereby permitting the right-hand end (Fig. 2) of lever c to rise and the left-hand end of lever c to fall thereby engaging tooth d' under stud d^2 on shipper arm 15. The lever e is then released whereupon the connec-

tions just described will return to their original position, the tooth d' lifting shipper 15 clear of the pin 14 and allowing clutch pinion 9 to engage the continuously rotating clutch member 11. Clutch pinion 9 makes one revolution and thereby raises the gate 51, pulls down the feeding and detecting roll 33 and actuates the reciprocating feed slide through link 29 to feed a blank from the bottom of the stack S in the hopper H as described in said Cogswell Patent No. 1,726,610. As pin 14 nears the end of its revolution it engages a bearing surface d^4 on the lower end of latch arm d (Fig. 2) and so disengages the tooth d' from the stud d^2 , permitting shipper 15 to fall and to disengage the clutch members 9 and 11 at the end of one revolution when the pin 14 rides up on the cam surface on the inner side of shipper 15.

The blank thus fed in passes underneath trip a holding the latter elevated and the latch arm d depressed with the tooth d' in position under stud d^2 . As soon as the blank passes out from under trip a the latter falls to the table, thereby lifting latch arm d and causing another actuation of the gate, roll 33, and feeding mechanism as just described. Thus it will be seen that another blank is fed in almost immediately after the trailing end of the preceding blank has passed clear of the detecting rolls 32, 33 and without waiting for the advance end of the preceding blank to reach a trip near the delivery end of the machine, as was necessary in said Cogswell patent.

In order to lock the slide bar 155, and consequently the skiving devices and stamping wheel, in the positions to which they have been adjusted by a blank passing between the detecting rolls, a new locking device is provided which is also controlled by trip a . As herein shown, this locking device consists of a rack bar h provided with teeth h' along its upper edge, pivoted at 18 to the slide bar 155, and a fixed holding blade i secured to the frame head of the machine. The rack bar h is actuated by the rock shaft f which extends from the bracket f' rearward to a bracket f'' on the other frame head, on which it is journaled at its rear end. Near its rear end rock shaft f has fixed to it an upwardly extending arm f^3 provided near its free end with a pin (or roller) f^4 which engages underneath a lever j fulcrumed on the frame of the machine at j' . The free end of lever j is made with a rearwardly projecting off-set j'' positioned immediately below the toothed rack bar h .

When the arm f'' occupies its upright position as shown in Fig. 5, its pin f^4 acts through lever j to hold the toothed edge of rack bar h in securely interlocked engagement with the fixed blade i , thereby positively locking the slide bar 155 (and the grad-

ing devices controlled thereby) against displacement. But when the trip *a* is raised rock shaft *f* will be turned in a clockwise direction as viewed in Fig. 5, thus lowering lever *j* and permitting rack bar *h* to swing downwardly and disengage from the fixed blade *i*. Thus it will be seen that when a blank is under trip *a*, holding it up, the locking devices *h*, *i*, will be disengaged, leaving the slide bar 155 free to respond to the measurements of the blank then passing through the detecting rolls 32, 33, and when the measurement is completed and the blank passes out from under trip *a* the trip will drop and the locking devices *h*, *i*, will be reengaged, thus locking the slide bar, and consequently the grading devices, in the position to which they have just been adjusted by said blank, and simultaneously the clutch 9 will be engaged and start the feeding in of the next blank. As the next blank approaches the detecting rolls the gate 51 will be automatically lifted by a cam (not shown) on shaft 27, and the detecting rolls will be opened or separated to receive the blank, all as fully described in said Cogswell Patent No. 1,726,610, thus admitting the incoming blank to the detecting rolls and also disengaging pawl 165 (which is controlled by the gate 51) from ratchet 163 on rock shaft 59 of the setting mechanism to leave the shaft 59 free to turn in response to successively thinner spots detected in the incoming blank. As soon as the preceding blank passes out from under trip 174 the other pawl 166 will also be disengaged from its ratchet 164, and will not again be engaged until the leading end of the succeeding blank reaches and lifts trip 174.

Although the gate 51 is lifted and a succeeding blank is introduced to the detecting rolls shortly after the preceding blank has left the detecting rolls and before it has passed the grading devices, the grading devices will be locked by *h*, *i*, in the adjustment corresponding to the thinnest measurement of the blank just measured when the trip *a* drops off from the rear end of that blank and will remain so locked until the leading end of the next succeeding blank lifts trip *a*. By that time the preceding blank will have entered between the skiving rolls 67, 68 and will lock or clamp the slide bar 155 immovable by the engagement of wedge blocks 156 and 157, notwithstanding lock *h*, *i*, is disengaged by the entrance of a succeeding blank.

The teeth *h'* of the locking member *h* are spaced to correspond to the width of the steps on the inclines of the stepped wedges 156, 157 (each step and each tooth representing a grade measurement of one-half of an iron according to usual practice) so that as the slide bar 155 is shifted endwise in response to the measurement of a blank, the teeth of the locking member *h*, which also

shifts endwise with bar 155, will correctly register with the fixed blade *i* in all positions of adjustment of the stepped wedges for grading the stock to the nearest iron or half iron. The teeth *h'* and also the engaging edge of the fixed locking blade *i* are preferably made V-shaped in order to justify or rectify the position of the slide bar 155 if it should happen to be left by the detecting rolls with the steps of the wedge blocks 156, 157 slightly out of register.

In the machine of said Cogswell Patent No. 1,726,610 as already explained, the marking mechanism was operated to stamp the grade mark on the stock by a trip (89 in said patent) actuated by the advance end of the blank just before it reached the marking wheel, and this same trip started the feeding-in of the next blank. As this trip has been eliminated by the present invention and replaced by the new trip mechanism above described, controlled by the following or trailing end of the blank, I have devised new mechanism for operating the marking device. When a blank enters between the skiving rolls 67, 68, which also feed the blank out of the machine, the upper roll 67 is lifted, and the mechanism for actuating the marking device is operated by this motion of roll 67 instead of by the trip of said former machine. As shown in Figs. 2 and 5, a link *k* is connected at its upper end by a strap *k'* to the shaft 75 of the upper roll 67. The lower end of link *k* is connected, with provision for adjustment, with one end of a lever arm *m*, fulcrumed at *m'* on the frame of the machine. The other end of lever arm *m* is connected by a link *n* to a bell crank *p* fulcrumed at *p'* on the frame of the machine. The upper end of bell crank *p* engages the usual latch of the usual shipper arm 80 by which the stamping mechanism is operated as described in said Cogswell Patent No. 1,726,610. It will be understood that when shipper arm 80 is swung to the right (Fig. 2) the slide carriage 185 carrying the stamping wheel, which has been rotatably adjusted in accordance with the measurement of the blank, is forced downwardly to mark the blank by the mechanism more fully described in said Cogswell patent. Thus when a blank enters between rolls 67 and 68, and raises roll 67, link *k* is pulled upwardly, thereby pulling link *n* downwardly, rocking bell crank *p* to the right, and swinging the shipper arm 80 to the right to effectuate the marking stroke of the type wheel 175.

In operation, as the incoming blank approaches the detecting rolls the gate 51 rises and the detecting roll 33 opens downwardly to admit the blank and after the blank is introduced between the detecting rolls the gate is again lowered on top of the blank and the detecting roll 33 closes upwardly against the blank. These actions take place as described in said Cogswell Patent No. 1,726,610. As

the advance end of the blank emerges from between the detecting rolls it engages and lifts the trip *a*, thereby unlocking the locking members *h* and *i* of slide bar 155, and holds the same unlocked as long as the blank is under trip *a*. At the time the blank lifts trip *a* the preceding blank will be between the skiving and feeding rolls 67 and 68 thereby clamping and locking the slide bar 155 immovable through the wedge blocks 156 and 157; consequently the action of the detecting roll 33 upon the incoming blank will not disturb the adjustment of the slide bar 155 and the grading devices controlled thereby as set by and for the preceding blank. In operating on larger sized blanks, such as shoe soles, the trip *a* is adjusted as close as possible to the detecting rolls 32, 33, since the advance end of a long blank will reach and enter the skiving rolls 67, 68, in time to clamp the wedge blocks 156, 157, before the next succeeding blank (which is started to be fed in when the trailing end of the preceding blank passes out from under trip *a*) reaches trip *a* and unlocks the locking members *h*, *i*. But if short blanks are being graded the trip *a* may be adjusted on arm *a'* to such position as to insure that the advance end of a blank passing through the machine will enter rolls 67, 68 before its trailing end operates through trip *a* to cause the succeeding blank to lift trip *a* and unlock the locking members *h*, *i*. When the incoming blank reaches and lifts trip 174, pawl 166 will engage ratchet 164 and hold the setting rock shaft 139 against movement in response to thicker areas in the blank but permitting setting shaft 139 to turn counter-clockwise (pawl 165 being held disengaged so long as the gate rests on top of the blank) in order to respond to successively thinner spots detected in the blank. When the rear or following end of the blank passes out from underneath the gate 51, pawl 165 will be set into ratchet 163 thus locking shaft 139 against rotation in either direction. As soon as the rear or following end of the blank passes out from under trip *a* the locking member *h* will engage the locking member *i* thus locking the slide bar 155 in the position to which it has just been adjusted by said blank, and simultaneously the clutch pinion 9 will be let into engagement with the continuously rotating clutch 11 thereby raising the gate 51, opening the detecting rolls and starting the feeding mechanism for feeding in another blank. The clutch pinion 9 will make one revolution and stop, as already explained. By the time said succeeding blank reaches trip *a* the preceding blank will have entered between rolls 67 and 68 so that the adjustment of the grading devices for the latter blank will be maintained by the engagement of the wedge blocks 156 and 157 notwithstanding the succeeding blank now lifts trip *a* and disengages locking member *h*. The

instant a blank enters between rolls 67 and 68, rolls 67 will be lifted thereby actuating the stamping mechanism through the connections *k*, *m*, *n* and *p*.

Instead of said novel mechanism for operating the stamping or marking device from the skiving rolls, the stamp operating trip of said Cogswell Patent No. 1,726,610 may be used, if desired, without affecting the use of that part of the present invention which includes the new tripping mechanism for controlling the admission of a succeeding blank and for locking and unlocking the grading devices.

It will be understood that if desired the machine may be fed by hand instead of automatically, in which case the feed link 29 and the feed slide or carriage actuated thereby may be omitted and the operator will shove a blank forward to the detecting rolls each time the gate 51 is elevated. In other respects the operation of the machine will be the same as described.

Unless otherwise required by the context, the term grading mechanism is used herein generically as explained in said Cogswell Patent No. 1,726,610.

I claim:

1. A grading machine of the kind having detecting mechanism, grading mechanism responsive to the detecting mechanism and means governing the admission of blanks to the detecting mechanism, comprising in combination mechanism controlled by the trailing end of a blank after it leaves the detecting mechanism to operate said governing means to admit a succeeding blank to the detecting mechanism, and simultaneously to lock the grading mechanism.

2. A grading machine of the kind having detecting mechanism, grading mechanism responsive to the detecting mechanism, means governing the admission of blanks to the detecting mechanism, and means for actuating a feeder for feeding blanks into the detecting mechanism, comprising in combination mechanism controlled by the trailing end of the blank after it leaves the detecting mechanism and before the blank leaves the machine to operate said governing means to admit a succeeding blank to the detecting mechanism and also to operate said feed actuating means.

3. A grading machine of the kind having detecting mechanism, grading mechanism responsive to the detecting mechanism, means governing the admission of blanks to the detecting mechanism, and means for actuating a feeder for feeding blanks into the detecting mechanism, comprising in combination mechanism controlled by the trailing end of a blank after it leaves the detecting mechanism to operate said governing means to admit a succeeding blank to the detecting mechanism and also to operate

said feed actuating means, and simultaneously to lock the grading mechanism.

4. A grading machine of the kind having detecting mechanism, grading mechanism responsive to the detecting mechanism, and means for actuating a feeder for feeding blanks into the detecting mechanism, comprising in combination mechanism controlled by the trailing end of a blank after it leaves the detecting mechanism and before the blank leaves the machine to operate said feed actuating means.

5. A grading machine of the kind having a pair of detecting rolls, one movable toward and from the other and grading mechanism responsive to the movable detector roll comprising in combination mechanism controlled by the trailing end of a blank after it leaves the detecting rolls to separate the detecting rolls to admit a succeeding blank.

6. A grading machine of the kind having a pair of detecting rolls, one movable toward and from the other, grading mechanism responsive to the movable detector roll and means governing the admission of blanks to the detecting rolls, comprising in combination mechanism controlled by the trailing end of a blank after it leaves the detecting rolls to operate said governing means and to separate the detecting rolls to admit a succeeding blank.

7. A grading machine of the kind having a pair of detecting rolls, one movable toward and from the other, grading mechanism responsive to the movable detector roll, and means governing the admission of blanks to the detecting rolls, comprising in combination mechanism controlled by the trailing end of a blank after it leaves the detecting rolls to operate said governing means and to separate the detecting rolls to admit a succeeding blank, and simultaneously to lock the grading mechanism.

8. A grading machine of the kind having detecting mechanism, grading mechanism responsive to the detecting mechanism, a drive shaft and a normally disengaged member associated with the drive shaft, comprising in combination mechanism controlled by the trailing end of a blank after it leaves the detecting mechanism and before the blank leaves the machine to engage said normally disengaged member with the drive shaft.

9. A grading machine of the kind having detecting mechanism, grading mechanism responsive to the detecting mechanism, mechanism including a trip in the path of the blank at the delivery side of the detecting mechanism for preserving in the grading mechanism the thinnest measurement of a blank as determined by the detecting mechanism, means governing the admission of blanks to the detecting mechanism and means for actuating a feeder for feeding blanks

into the detecting mechanism, comprising in combination a second trip located in the path of the blanks at the delivery side of the detecting mechanism and mechanism operated independently of the first trip by said second trip when the second trip is actuated by the trailing end of the blank to operate said governing means to admit a succeeding blank to the detecting mechanism and also to operate said feed actuating means.

10. A grading machine of the kind having detecting mechanism and grading mechanism responsive to the detecting mechanism comprising in combination locking means for the grading mechanism, and mechanism controlled by the advance end of a blank emerging from the detecting mechanism to unlock said locking means, and by the trailing end of said blank after it leaves the detecting mechanism to lock said locking means.

11. A grading machine of the kind having detecting mechanism, grading mechanism responsive to the detecting mechanism and means governing the admission of blanks to the detecting mechanism, comprising in combination locking means for the grading mechanism, and mechanism controlled by the advance end of a blank emerging from the detecting mechanism to unlock said locking means, and by the trailing end of said blank after it leaves the detecting mechanism to lock said locking means and to operate said governing means to admit a succeeding blank to the detecting mechanism.

12. A grading machine of the kind having detecting mechanism, grading mechanism responsive to the detecting mechanism, means governing the admission of blanks to the detecting mechanism, locking means for the grading mechanism and means for actuating a feeder for feeding blanks into the detecting mechanism, comprising in combination mechanism controlled by the advance end of a blank emerging from the detecting mechanism to unlock said locking means and by the trailing end of said blank after it leaves the detecting mechanism to lock said locking means and to operate said governing means to admit a succeeding blank to the detecting mechanism and to operate said feed actuating means.

13. A grading machine of the kind having detecting mechanism, grading mechanism responsive to the detecting mechanism, means governing the admission of blanks to the detecting mechanism, locking means for the grading mechanism and means for actuating a feeder for feeding blanks into the detecting mechanism, comprising in combination a trip located in the path of the blanks at the delivery side of the detecting mechanism, mechanism operated by said trip when the trip is actuated by the advance end of a blank to unlock said locking mechanism and

mechanism operated by said trip when the trip is actuated by the trailing end of the blank to lock said locking means and to operate said governing means to admit a succeeding blank to the detecting mechanism and to operate said feed actuating means.

14. A grading machine of the kind having detecting mechanism, grading mechanism responsive to the detecting mechanism, and locking means for the grading mechanism, comprising in combination a trip located in the path of the blank at the delivery side of the detecting mechanism and adapted to engage each blank throughout its length, mechanism operated by said trip when the trip is actuated by the advance end of a blank to unlock said locking means and to hold the same unlocked so long as the trip contacts with the blank, and mechanism operated by said trip when the trip is operated by the trailing end of the blank to lock said locking means.

15. A grading machine of the kind having detecting mechanism, grading mechanism responsive to the detecting mechanism, means governing the admission of blanks to the detecting mechanism and locking means for the grading mechanism, comprising in combination a trip located in the path of the blank at the delivery side of the detecting mechanism and adapted to engage each blank throughout its length, mechanism operated by said trip when the trip is actuated by the advance end of a blank to unlock said unlocking means and to hold the same unlocked so long as the trip contacts with the blank, and mechanism operated by said trip when the trip is operated by the trailing end of the blank to lock said locking means and to operate said governing means to permit a succeeding blank to the detecting mechanism.

16. A grading machine of the kind having detecting mechanism, grading mechanism responsive to the detecting mechanism and means for actuating a feeder for feeding blanks into the detecting mechanism, comprising in combination locking means for the grading mechanism, and mechanism controlled by the advance end of a blank emerging from the detecting mechanism to unlock said locking mechanism and by the trailing end of said blank after it leaves the detecting mechanism to lock said locking mechanism and to operate said feed actuating means.

17. A grading machine of the kind having detecting mechanism, grading mechanism responsive to the detecting mechanism and means for actuating a feeder for feeding blanks into the detecting mechanism, comprising in combination locking means for the grading mechanism, a trip located in the path of the blanks at the delivery side of the detecting mechanism, mechanism operated by said trip when the trip is actuated by the advance end of a blank to unlock said locking

mechanism, and mechanism operated by said trip when the trip is actuated by the trailing end of the blank to lock said locking means and to operate said feed actuating means.

18. A grading machine of the kind having detecting mechanism, grading mechanism responsive to the detecting mechanism and means governing the admission of blanks to the detecting mechanism, comprising in combination mechanism adapted to be operated by a blank immediately upon its delivery from the detecting mechanism to lock the grading mechanism and to operate the governing means to admit a succeeding blank to the detecting mechanism.

19. A grading machine of the kind having detecting mechanism, grading mechanism responsive to the detecting mechanism and means for actuating a feeder for feeding blanks into the detecting mechanism, comprising in combination mechanism adapted to be operated by a blank immediately upon its delivery from the detecting mechanism to lock the grading mechanism and to operate said feed actuating means.

20. A grading machine of the kind having detecting mechanism, grading mechanism responsive to the detecting mechanism and means for actuating a feeder for feeding blanks into the detecting mechanism, comprising in combination locking means for the grading mechanism, a trip in close proximity to the detecting mechanism on the delivery side thereof and in the path of the blank adapted to be operated by a blank emerging from the detecting mechanism, and mechanism controlled by said trip for unlocking said locking means when a blank contacts with the trip and maintaining the locking means unlocked so long as the blank remains in contact with the trip, and for locking said locking means when the blank passes out of contact with the trip, and mechanism controlled by said trip when the blank passes out of contact with the trip for operating said feed actuating means.

21. A grading machine of the kind having detecting mechanism, a slide bar, means to adjust the slide bar in accordance with the detecting mechanism, and grading mechanism controlled by the slide bar, comprising in combination mechanism operated by each blank upon its delivery from the detecting mechanism for locking the slide bar in its adjusted position and for maintaining said slide bar locked until the advance end of the next succeeding blank emerges from the detecting mechanism.

22. A grading machine of the kind having detecting mechanism, a slide bar, means to adjust the slide bar in accordance with the detecting mechanism and grading mechanism controlled by the slide bar, comprising in combination a locking member movably mounted on the slide bar, a fixed locking

- member, and mechanism operated by each blank upon its delivery from the detecting mechanism for moving the movable locking member into engagement with the fixed locking member to lock the slide bar in its adjusted position. 5
23. A grading machine of the kind having detecting mechanism, a slide bar, means to adjust the slide bar in accordance with the detecting mechanism and grading mechanism controlled by the slide bar, comprising in combination a toothed rack bar movably mounted on the slide bar, a fixed locking member adapted to engage the teeth of the rack bar, and mechanism operated by each blank upon its delivery from the detecting mechanism for moving the rack bar into engagement with the fixed locking member to lock the slide bar in its adjusted position. 10
24. A grading machine of the kind having detecting mechanism, grading mechanism responsive to the detecting mechanism and means for actuating a feeder for feeding the blanks into the detecting mechanism, comprising in combination mechanism controlled by successive blanks passing through the machine so organized and arranged as to operate the feed actuating means to feed successive blanks into the machine each before the next preceding blank has left the machine and in uniform spaced relation between the trailing end of one blank and the advance end of the next succeeding blank irrespective of the length of the blanks. 15
25. A grading machine of the kind having detecting mechanism, grading mechanism responsive to the detecting mechanism, mechanism including a trip in the path of the blank at the delivery side of the detecting mechanism for preserving in the grading mechanism the thinnest measurement of a blank as determined by the detecting mechanism, and means governing the admission of blanks to the detecting mechanism, comprising in combination a second trip located in the path of the blanks in advance of the first trip and mechanism operated independently of the first trip by said second trip when the second trip is actuated by the trailing end of the blank to operate said governing means to admit a succeeding blank to the detecting mechanism. 20
26. A grading machine of the kind having detecting mechanism, grading mechanism responsive to the detecting mechanism, mechanism including a trip in the path of the blank at the delivery side of the detecting mechanism for preserving in the grading mechanism the thinnest measurement of a blank as determined by the detecting mechanism, and means for actuating a feeder for feeding blanks into the detecting mechanism, comprising in combination a second trip located in the path of the blanks in advance of the first trip and mechanism operated in- 25
- dependently of the first trip by said second trip when the second trip is actuated by the trailing end of the blank to operate said feed actuating means. 30
27. A grading machine of the kind having detecting mechanism, grading mechanism responsive to the detecting mechanism, mechanism including a trip in the path of the blank at the delivery side of the detecting mechanism for preserving in the grading mechanism the thinnest measurement of a blank as determined by the detecting mechanism, means governing the admission of blanks to the detecting mechanism, and means for actuating a feeder for feeding blanks into the detecting mechanism, comprising in combination a second trip located in the path of the blanks in advance of the first trip and mechanisms operated independently of the first trip by said second trip when the second trip is actuated by the trailing end of the blank to operate said governing means to admit a succeeding blank to the detecting mechanism and also to operate said feed actuating means. 35
- Signed by me at Boston, Massachusetts, this tenth day of December, 1929.
- JAMES W. JOHNSTON.
